UNITED STATES PATENT OFFICE.

MAX GARBEL, OF CHICAGO, ILLINOIS.

TYPE-WRITING MACHINE.

1,305,893.

Specification of Letters Patent. Patented June 3, 1919.

Application filed May 2, 1918. Serial No. 232,016.

To all whom it may concern:

Be it known that I, MAX GARBEL, a citizen of the United States, residing at Chicago, in the county of Cook and State of Illinois, have invented certain new and useful Improvements in Type-Writing Machines, of which the following is a full, clear, and exact description.

The invention relates to improvements in 10 a typewriting machine and particularly to an improved form of type bar action for a typewriting machine.

It is the primary object of the invention to provide an improved form of type bar 15 action adapted for use in small writing machines of a compact form commonly called portable machines. Such machines differ in construction from the standard office machines in that it is desirable that the mechanism be so arranged that the machine will 20 occupy a minimum amount of space when it is desired to carry the same as baggage by travelers, persons engaged in military service and the like.

25 The invention is applicable to typebar actions in which the typebars reciprocate, as distinguished from actions in which the typebars are pivoted. Heretofore typebars of the reciprocating type have been operated 30 from their corresponding key levers through intermediate levers and link connections or sliding connections. Sliding connections result in a sluggish action due to friction and the difficulty of properly lubricating the 35 slides. Intermediate levers, or sub-levers connected with reciprocating typebars through link or sliding connections have commonly necessitated the use of sub-levers or intermediate levers of considerable length 40 in order to get the necessary degree of throw to properly operate the typebars. This has resulted in a machine of considerable height because of the necessary separation of key levers and typebars to accommodate the 45 intermediate lever mechanism.

It is an object of the invention to provide a segmental gear connection with each of the type-bars, the segmental gear being actuated by a suitable connection with the corresponding key levers whereby the maximum degree of throw may be imparted to the typebars from the key levers with a minimum degree of normal separation between type-bar and key lever, resulting in a 55 compact machine.

It is a further object of the invention to provide a form of rolling support and guide for the tail end of the type-bar, thus making it possible to dispense with the usual lower tail end guides on reciprocating type bar 60 constructions and making it possible to use a much shorter type-bar, and still obtain the maximum amount of throw, while at the same time securing a decided advantage not only in compactness but also in ease of operation due to the elimination of unnecessary friction of all sliding connections which are dispensed with in my construction.

Other objects of the invention will appear from the following specification which is directed to the preferred embodiment of my invention as shown in the drawings forming a part of the specification and pointed out more particularly in the appended claims.

In the said drawings Figure 1 is a top plan 75 view showing the arrangement of the parts associated with the type bar action of my machine with parts of the machine main frame and platen broken away.

Fig. 2 is a detail sectional view through 80 the machine taken approximately on line 2-2 of Fig. 1. In this view parts of the carriage for supporting the platen and for shifting same are omitted as the same forms no part of the invention.

Fig. 3 is a broken detail sectional view 85 illustrating the construction of the type bar action, the view being taken approximately on line 3-3 of Fig. 2.

The invention is preferably incorporated 90 into a construction having a main supporting frame of special and irregular construction as indicated by the reference character 10. This frame is preferably of integral construction and the side portions of the frame are designated by the reference character 10^a, the back side of the frame at 10^b and the front at 10^c. The frame is provided with four or more downwardly extending projections or legs 10^d by which the 95 machine may be supported upon a flat surface as upon a table top. 11 designates generally the platen of the ordinary cylindrical form. It will be understood that the platen will be supported in the ordinary manner 100 upon a carriage of any desired construction mounted upon the main frame 10. No carriage is shown in the drawing as this forms no part of the present invention.

Coöperating with the platen 11 are the 110

printing types 12^a, the latter being secured to and forming a part of the composite type bars which are designated generally by the reference character 12, and are arranged in 5 a type bar frame on the upper side of the machine above the main frame 10, the arrangement of the type bars being preferably in the form of a segment of a circle with the longitudinal axis of each of the type bars 10 12 intersecting the printing surface of the platen at the normal printing point which is designated by the reference character 11^a, (Figs. 1 and 2). The composite type bars 12 preferably consist of the type members 15 12^a extending vertically and provided with three printing characters as designated by the reference characters 12^b, 12^c and 12^d. The type members 12^a are each secured to the body portion of the type bar which is 20 designated generally by the reference character 12^e, Fig. 2, and consists preferably of an irregular metal stamping having a main body portion in the general form of a rectangle, the central part of the body 25 portion being cut away for lightness. The body portion 12^e of the type bar has an extension from the rectangular portion which is designated in Fig. 2 by the reference character 12^f, the latter being in 30 the form of a toothed rack bar, the teeth being designated by the reference character 12^g. The toothed rack bar portion 12^f of the type bar 12 is normally in engagement with a segmental toothed bell crank lever 35 designated generally by the reference character 13, the teeth of the segment or gear thereon being designated at 13^a. The rack portion 12^f of the type bar therefore rests normally upon the toothed segmental portion 40 or gear of the bell crank lever 13 and is carried thereby, while the forward end of the type bar is carried upon the surface of a plate 14, which is supported upon the frame 15 which carries the type bar action. That 45 is to say the lower extremity of the forward end of the type bar has frictional engagement with the top surface of the plate 14 but is guided in its reciprocating movement to and from the printing surface of the 50 platen in order to insure contact at the normal printing point by reason of the fact that the separated body portions 12^e and 16^a of the type bar are guided in vertical slots in a comb or guide member which is 55 designated generally by the reference character 16 and is secured as indicated by the screws 17 to the type bar action supporting frame 15 (see Fig. 2). The slotted comb or guide member 16 is curved in the arc of 60 a circle to conform with the circular arrangement of the type bar actions by which each of the printing faces of the type bars are caused to impinge upon or strike the normal printing point upon the surface of 65 the platen. It should be here noted as will

be apparent from an inspection of the top plan view of the type portions of the various type bars 12^a as shown in the top plan view of Fig. 1 that the printing faces of each of the type are so constructed that the printing face of each type is arranged parallel with the printing face of the platen regardless of the angle at which the type bar and the type thereon moves to engage the platen at the normal printing point. The 75 type members 12^a are caused to extend some distance above the upper branch 12^e of the type bar in order to form a suitable portion for contact with the cushioning member 18 as shown in both Figs. 1 and 2. This cushion may be of felt or other suitable cushioning material and secured to the concavely curved face of the plate 19 secured as indicated by screws 20 to the upper portion 21 of the type bar action frame. Each of the 80 type bar members 12^a will therefore normally rest against the cushioning part 18 which will also absorb any tendency to vibration on the part of the type bar action upon the return or retraction of the type bar 85 action after contact with the printing face of the platen. 90

I prefer to extend the lower edge of the plate 19 below the frame 21 as shown in Fig. 2 thereby forming an upper retaining 95 ledge for coöoperating with the upper surface or edges of the type bars 12^e for preventing any tendency on the part of the type bar to rise at the forward or printing end. At the front side of the curved frame 100 21 I secure by suitable screws as indicated at 22 an additional type bar guide plate 23, a portion of which is shown in detail in Fig. 3. This guide plate 23 is of special construction being notched as indicated at 105 23^a to receive a coöoperating portion at the upper edge of each of the type bars 12. The body portions 12^e of the type bars which are provided with the toothed rack portions 12^f have attached to them on each side by 110 means of rivets 12^b spaced plates 12ⁱ. The plates 12ⁱ are secured to the rack portions 12^f of the type bars so that along the upper edge of the type bar about one sixteenth of an inch of the body of the type bar member 12^f projects above the upper edges of the side plates 12ⁱ. This projection of the type bar member 12^f is preferably just a trifle more than the depth of the slots or notches 23^a in the guide curved member 23 115 120 so that the member 12^f only engages with the plate and the side members of the type bar clear the guide plate. The plates 12ⁱ are preferably allowed to extend a short distance below the lower extremities of the 125 teeth 12^b of the rack on the type bar. The segmental toothed portion of the sub-lever or bell crank 13 having the teeth 13^a for coöoperating with the teeth of the type bar is also provided with curved side plates 130

13^b, one on each side of the segmental toothed portion, these being likewise secured to the bell crank lever by rivets 13^c. The arrangement of the plates 13^b upon the sub-lever 13 together with the plates 12ⁱ upon the type bars, it will be seen, is such that these plates are normally in engagement with each other throughout all relative movement of the parts so that there is no tendency for the teeth of the type bar racks to ride upon the teeth of the segments of the bell crank or sub-levers 13 as the weight of the type bars will be carried upon the curved upper surface of the plates 13^b, thus affording a rolling action and avoiding friction since proper meshing of the teeth of the gears will be insured at all times without any tendency for the teeth of the gears by reason of wear or any shifting of relation to get out of proper mesh, thus insuring uniformity of coöperation between the parts and easy action at all times throughout the life of the machine since the plates 12ⁱ and 13^b may obviously be constructed so as to preclude the possibility of any considerable variation in the meshing of the gears due to wear of the parts. Obviously each of the longitudinal movable type bars 12 will have a coöperating sub-lever or gear segment 13 as illustrated in Figs. 2 and 3. The gear segments or sub-levers 13 are arranged in the arc of a circle being supported in the slotted segment frame 30, which is secured by screws 31 to the front curved edge of the type bar action supporting frame 15. The gear segments or sub-levers 13 are secured on the common curved pivot pin or wire 32 in the segment 30. Links 33 connect arms 13^e of the sub-lever or segments 13 with key levers 34 which are pivoted at 35 to the main frame 10.

It will be seen that when an operator depresses one of the keys 34^a and the corresponding key lever 34 the pull of the link 33 will rock the sub-lever or segment 13 to the position shown in dotted lines in Fig. 2, which will result in the longitudinal movement of the type bar 12 to the position of the type bar also shown in dotted lines in Fig. 2 where the printing face 12^e of the type bar will contact with the printing point 11^a on the platen. The key levers 34 are held in their normal or elevated position shown in full lines in Fig. 2 by means of suitable compression springs 37 interposed between the levers and the supporting bar 38 shown in section in Fig. 2 as attached to the main frame 10. The springs 37 are made adjustable by means of screws and the compression power of the springs may be adjusted to return the type bar and its operating mechanism to the normal or retracted position as shown in full lines 65 in Fig. 2 after being operated to the print-

ing position. A type guide as indicated by the reference character 40, Figs. 1 and 2 is preferably employed to properly position the printing types when the type bars are actuated to the printing position. 41 70 is a universal bar positioned so as to be actuated by the movement of any one of the key levers for the purpose of operating the carriage escapement in the usual manner in machines of this character. 42 is 75 the usual space bar connected through levers 43 with the carriage escapement of the machine in the usual or any desired manner. 50 is a covering plate which may be conveniently arranged as a shield over 80 the top of the machine covering the type bar actions to any extent desired, and at the same time may be utilized for applying the name of the machine thereto or for ornamental purposes. 85

With the improved form of type bar action herein shown, described and claimed I am enabled to construct a machine having the capabilities of standard full sized machines both as to ease of operation and 90 capacity, for doing the most difficult work that is obtainable in any of the standard sized machines and at the same time keeping the size of the machine within the limits where it will occupy one third or even 95 less than one third of the space ordinarily occupied by ordinary typewriting machines of standard design.

In order that the invention might be understood the details of the preferred embodiment have been set forth but it is not desired to be limited to the exact details of the type bar action shown for it will be apparent that persons skilled in the art may vary the construction within certain limits 105 without departing from the purpose and spirit of the invention.

I claim:

1. In a type bar action for typewriting machines, the combination with a longitudinally reciprocable type bar provided with a rack consisting of a plurality of teeth consecutively and horizontally arranged along one side of the type bar, a key lever, a pivoted sub-lever provided with a curved toothed segmental portion engaging the teeth of the rack on the type bar, a stationary guide adjacent the toothed portion of the type bar for preventing lateral movement thereof, coöperating means on the sub-lever and type bar adjacent the engaging portions thereof for preventing lateral relative movement between the said sub-lever and type bar, and means for operatively connecting the key lever with the sub-lever. 115 120 125

2. In a type bar action for typewriting machines, the combination with a longitudinally movable type bar provided with a toothed rack portion, a guide plate secured to the toothed rack portion of the type bar 130

- adjacent the teeth thereon, a pivoted key lever, a pivoted sub-lever provided with a curved toothed segmental portion engaging the teeth of the rack on the type bar, a 5 curved plate secured to the toothed segmental portion of the pivoted sub-lever adjacent the teeth thereon and being provided with a curved surface adapted to coöperate with the guide plate secured to the toothed 10 rack portion of the type bar, and means for connecting the key lever with the sub-lever for actuating the latter and the type bar upon the movement of the key lever.
3. In a type bar action for typewriting machines, the combination with a longitudinally movable type bar provided with a 15 rack portion, guide plates secured to the typebar on each side of the said toothed portion thereof and substantially inclosing 20 the teeth within the space formed therebetween, a pivoted sub-lever provided with a toothed segmental portion engaging the teeth of the toothed or rack portion of the type bar, curved guide plates secured on 25 opposite sides of the toothed segmental portion of the sub-lever and having curved surfaces adapted to engage the guide plates of the type bar whereby to regulate the meshing of the teeth on the type bar and 30 sub-lever, and means for connecting the key lever with the sub-lever for actuating the latter and the type bar under the control of the key lever.
4. In a type bar action for typewriting machines, the combination with a longitudinally movable type bar provided with a 35 toothed or rack portion, a pivoted key lever, a pivoted sub-lever provided with a curved toothed segmental portion engaging the 40 teeth of the rack or the type bar, means for connecting the key lever with the sub-lever for actuating the latter and the type bar through the movement of the key lever, and means for determining the meshing of the 45 teeth of the type bar and the teeth of the curved toothed segmental portion of the sub-lever comprising a pair of spaced plates secured adjacent the toothed portion of the type bar and a pair of coöoperating curved 50 spaced plates secured adjacent the toothed segmental portions of the sub-lever.
5. In a type bar action for typewriting machines the combination with a longitudinally reciprocable type bar provided with a toothed rack portion at one end and a type 55 bearing portion at the other end, a stationary guide for the bar adjacent the type bearing end, a key lever, a pivoted sub-lever provided with a curved toothed segmental portion in engagement with the under side of 60 the toothed rack portion of the type bar, and coöperating means on the type bar and the toothed segmental portion of the sub-lever whereby to afford a rolling support for the toothed end of the rack bar, and 65 means for operably connecting the key lever with the sub-lever.
6. In a type bar action for typewriting machines the combination with a plurality of longitudinally reciprocable type bars 70 each provided with toothed racks consisting of a plurality of teeth consecutively and horizontally arranged along one side of the type bar, the type bars being arranged radially in a common plane and having 75 suitable guiding devices whereby upon the reciprocation of each of the type bars the printing face thereof will intersect a common printing point, pivoted key levers and pivoted sub-levers corresponding with each 80 of the said type bars, the said sub-levers being each provided with a toothed segmental portion engaging the toothed portion of the type bars, means for connecting each of the type bars with its corresponding 85 sub-lever whereby the actuation of the key lever will move the sub-lever and the type bar, means providing a sliding support for the longitudinally reciprocable type bars 90 near their ends provided with type, and coöperating means on the said toothed segmental portions of the sub-levers and the toothed rack portions of the type bars whereby the toothed ends of the type bars have a rolling engagement with and are 95 carried by the toothed segmental portions of the sub-levers.

In testimony whereof I have signed my name to this specification, in the presence of two subscribing witnesses on this 26th 100 day of April, A. D. 1918.

MAX GARBEL.
